APPARATUS FOR FORMING SUBTER-
RANEAN CAVITIESFrederick Squires, Champaign, Ill., assignor to
The Dow Chemical Company, Midland, Mich.,
a corporation of Michigan

Application December 29, 1938, Serial No. 248,187

6 Claims. (Cl. 255—76)

This invention relates to a method and apparatus for forming or enlarging a cavity in a water, gas, oil, brine or other type well hole, and more specifically it relates to a method and apparatus for enlarging selected portions of a well hole, or forming, or enlarging a cavity in certain selected portions of the well.

This invention is directed to a method and apparatus for forming or enlarging a cavity in certain selected portions of a water, gas, oil or other type well hole, to give a result similar to a shot hole or a hole that has been underreamed or otherwise enlarged. By the practice of this invention such cavities may be formed at a selected point in the well hole so that there may flow into the cavity, and therein accumulate, the products of the well. This invention enables a cavity of symmetrical form and controllable size to be made disposed about the main well hole, and which is formed without any shock, disruption or fracture to the surrounding formation as would be the case if it were formed by shooting.

With this invention a cavity is formed in the well hole by the action of mechanical cutting teeth, or other cutting and scraping means, the action of which is augmented by a chemical, such as an acid or other agent to dissolve, or partly dissolve, the formation wherein the cavity is to be formed.

The formation of such a cavity in a well hole as here contemplated, especially when formed in an oil or gas well, will not only of itself greatly enhance the production of the well, but will serve to condition the well in a manner more favorable for such reconditioning thereof, such as by acidizing and numerous other types of well treatments.

Specifically, it is believed that this invention will find its, or one of its, greatest utilizations in forming or enlarging cavities in those parts of a well hole which are limestone or of other calcareous formation, so that the drainage of the products of the well into the well hole will be greatly assisted and the production of the well thereby increased; and additionally a well formed with a cavity by the practice of this invention will be in a materially better condition for any of the various types of acidizing or other chemical treatments.

The principal object of this invention is to provide a method and apparatus for forming, or enlarging a cavity in selected portions of a well hole.

Another object is to provide a mechanical means for forming or enlarging a cavity in a selected portion of a well hole.

Another object is to provide a means for em- 55

ploying a chemical medium for forming or enlarging a cavity in a selected portion of a well hole.

Another object is to provide mechanical means and a chemical medium for forming or enlarging a cavity in a well hole, wherein both said means and medium augment and assist the action and function of the other.

Another object is to provide a method and apparatus for forming, or enlarging, a cavity in a well hole so that it is of uniform outline, of controllable size and symmetrically disposed about the well hole.

Another object is to form, or enlarge, such a cavity in a well hole so as to assist and increase the production of the well.

Another object is to form, or enlarge, such a cavity in a well hole so as to facilitate the reconditioning of the well, as by acidizing, etc.

Still another object is to form, or enlarge, a cavity in a selected portion of a well hole, for the above and other purposes, in such a manner that the formation in which the cavity is formed or enlarged is not subject to shock, disruption or fracture.

And still another object of this invention is to form such cavities with the aid of hydrochloric acid in that part of a well hole which is at least partly composed of limestone or other calcareous or chemical soluble matter.

Attention is now directed to the drawings illustrating the method and apparatus for practicing this invention, which comprise a part of this specification, and wherein:

Fig. 1 is a longitudinal view partly in vertical cross-section of a side view of one form of apparatus for realizing this invention.

Fig. 2 is a longitudinal view of the apparatus illustrated in Fig. 1, and is a vertical cross-sectional view of a part thereof taken from the front and illustrating certain details thereof.

Fig. 3 is a transverse cross-sectional view of Fig. 2 taken on line 3—3 thereof looking in the direction of the arrows.

Fig. 4 is a longitudinal view partly in cross-section of the same apparatus shown in Fig. 1, but here illustrating the apparatus lowered into a well hole and engaged in forming a cavity therein.

Fig. 5 is a transverse cross-sectional view of Fig. 4 taken on line 5—5 thereof.

Fig. 6 is a transverse view partly in cross-section of a detail of Fig. 4 taken on line 6—6 thereof.

Fig. 7 is a view similar to Figs. 1 and 4 but shows the apparatus starting the forming of a cavity in a well hole.

It is to be clearly understood that this invention relates to both an apparatus and a method for forming or enlarging a cavity, or cavities, in a well hole, and that while only one general embodiment of the apparatus for practicing this invention is herein disclosed and described, no intent is made to so limit this invention solely thereto, or to the practice of the method only with such apparatus.

With reference now to Fig. 1 wherein there is illustrated one form of apparatus for practicing this invention, it will be seen that the same comprises an elongated cylindrical housing 10 which is of a diameter sufficiently small enough to enable it to be lowered into the well hole. The upper end of the housing is formed with a head 11 provided with a bore 12 passing therethrough in alignment with the longitudinal axis of the housing, while the lower end of the housing 10 is formed with the inwardly projecting annular flange 13, the upper surface of which constitutes an annular shoulder 14. A shaft 15, of reduced diameter relative to that of the housing 10 and disposed in longitudinal alignment therewith, is capable of limited movement upwardly thereinto, and is provided with a tapered head 16. Head 16 is formed with a flange 17 adapted to seat upon the shoulder 14 of the housing and suspend the shaft from housing 10, and to limit the downward movement of shaft 15 therefrom. At the lower end of shaft 15 there is formed an annular shoulder 18, adapted upon the upward movement of shaft 15, and/or the downward movement of housing 10, to contact the flange 13 of housing 10 and thereby limit the upward movement of the shaft thereinto. Shaft 15 is formed preferably of a length which, from flange 17 to shoulder 18, is shorter than the distance between the pivot points B and C, the function of which points will hereafter be explained. In the lower end of shaft 15 there is formed a circular recess 19 and a similar recess 20 is formed in the top of the stub shaft or foot 21. Into these recesses there is fitted the circular dowel pin 22 which is upset at its ends so as to hold the two shafts together and yet permit independent rotary movement thereof. The shaft or foot 21 may be of any convenient or desired length and is provided on the bottom with a series of prongs or anchors 23 for engagement with the bottom of the well hole.

A longitudinal section of the housing 10, extending from near the top to near the bottom thereof, is cut away to form therein the window 24, which is also illustrated in Figs. 4 and 5.

Referring now to Figs. 1 and 2, it will be seen that there is provided a section of pipe or tubing 25, to which may be coupled numerous similar sections or lengths so that they may be made to reach from the surface to permit lowering the housing to any desired depth in the well hole. The pipe extends through the bore 12 formed in head 11 of the housing 10 and into the housing where it terminates in an elbow 26 which is pivotally connected to elbow 27 to form the pivot point A, which is also shown in Figs. 4 and 7. To elbow 27 is connected a hollow arm or section of pipe 28, which is in communication with pipe 25, and terminates in elbow 29 which makes a pivotal connection with a T-like pipe fitting 30 to form the pivot point B. Extending through the fitting 30 there is a pipe or hollow arm 31 which is in communication with pipe 28 and is closed at its upper end 31', and has its lower end 31" swaged closed and provided with the hole

32 which is pivoted on pin 33 carried by the ear 34 of the shaft head 16, so as to pivotally mount the pipe 31 upon pin 33 to comprise a third pivot point C. The joint between pipes 25 and 28, effected by the elbows 26 and 27 respectively to comprise pivot point A, and the joint between pipe 28 and 31, effected by the elbow 29 and the T-like fitting 30 to comprise pivot point B, are both leakproof pivotal points in these pipe connections.

It will be appreciated by reference to Figs. 1, 2, 4 and 7, that pipe 31 has formed on one side thereof, and preferably in longitudinal alignment, a plurality of stub pipes 35, which are in communication with the interior of pipe 31, as shown in Fig. 6. With reference to said last mentioned figure it will be seen that in the interior of each of the stub pipes 35 there is positioned a disc 36 provided with a plurality of ports, such as the one 37. A stem 38 slidably passes through the center of disc 36 and has formed on its lower end a conical shaped head 39, each of which heads serve as a cutting tooth or scraping member to help form the cavity in the well hole as will be fully appreciated from the following description. The point or cap of head 39 may be formed with a tip 40 of some special material such as will withstand a great amount of wear, such as specially hard steel or a diamond tip. Keyed to the stem 38 is a disc 41 adapted to normally be forced by one end of compressed spring 42 against the disc 36 to close and cover the ports therein. The other end of spring 42 abuts against the stop member 43. By this arrangement spring 42 normally maintains the disc 41 in contact with disc 36 and keeps the ports therein closed so that liquid in pipe 31 cannot escape, but when pressure is applied to the tip 40 mounted on stem 38, as by the head 39 contacting a solid mass such as the formation in the well hole, then stem 38 is depressed and disc 41 is moved upwardly against the action of spring 42 and the ports 37 are uncovered to allow the escape of liquid from pipe 31 and stub pipe 35 through the ports 37. A collar 44 may be positioned on stem 38 adjacent the head 39 to prevent the head from covering the ports 37 when the head is forced inwardly.

With specific reference to Figs. 2 and 3 it will be seen that the pipe section 25 has secured thereto in any convenient manner, as by a key or welding, a guide 45 which is disposed within the housing 10, and which at the ends thereof terminates in flared heads 46 which are slidably mounted in oppositely disposed grooves or channels 47 formed longitudinally of the interior of housing 10 and extending substantially the length thereof. By a consideration of Fig. 3 it may more clearly be seen how the guide 45 is secured to the pipe 25 with the heads 46 of the guide disposed in the channels 47 of the housing 10. Fig. 5 likewise illustrates this guide feature, but more specifically with relation to Fig. 4. In Fig. 5 the guide 45 has slid down the channels 47 until it is at a point opposite a portion of the window 24 formed in the housing 10.

Pivot points A and C are arranged in vertical alignment, but pivot point B is preferably out of alignment with respect thereto and is caused to be disposed a slight distance to the right of these points by the leaf spring 48 mounted on the interior of housing 10 which prevents point B from moving into vertical alignment with points A and C. Such arrangement assists in causing the pipes 28 and 31 to project out of the housing

10 and into the well hole, as will hereinafter be explained.

When it becomes desirable to form a cavity in a well hole, as by the practice of this invention, the apparatus assembly, as illustrated in Fig. 1, is lowered into the well hole with the pipes or hollow arms 28 and 31 retracted in the housing 10 which is suitably suspended from the surface by sufficient lengths of pipe or tubing until it has reached the proper depth opposite the formation in which it is desired to form the cavity or enlarge the hole. During the course of lowering the apparatus into the hole its various parts will maintain their relative positions in the same manner as illustrated in Fig. 1, i. e., the housing 10 is suspended from the tube 25 which is kept from pulling out through the top thereof by the guide 45, the shaft 15 is suspended from the housing 10 by virtue of the engagement made between the flange 17 and the shoulder 14 of these two members respectively, and the foot 21 is connected to and dependent from the shaft 15. The weight of the entire assembly while being lowered into the well hole is supported by the tube 25.

When the foot 21 strikes the bottom of the hole, the teeth or prongs 23 thereof will dig into the bottom of the hole and at first the weight of the foot 21 and shaft 15 will be supported on the bottom of the hole and as the tube 25 and housing 10 are continued to be lowered into the hole the lower end of the housing 10 will slide down over the shaft 15 until the flange 13 formed on the housing abuts the shoulder 18 of the shaft at which time the weight of the housing is then resting on the foot 21 and they both are then supported by the bottom of the well hole and their weight is no longer suspended from the tubing 25. It will be well to have interchangeable feet, such as the foot 21, which are of varying lengths so that the housing 10 may be conveniently supported any desired distance off of the bottom of the well so as to be opposite the formation wherein the cavity is to be formed.

When foot 21 comes to rest on the bottom of the well hole, continued lowering of the tubing 25 will cause guide 45 to slide downwardly in the channel 47 of the housing and also force pipe 28, connected to pipe 25, to move downwardly therewith and pivot at points A and B, and as pipe 31 is stationarily pivoted at point C it will be caused to pivot at points B and C with the result that the two pipes 28 and 31 will be caused to project out of the housing 10 through the window 24 thereof and into the well hole. Such movement of pipes 28 and 31 will result from the above described lowering of pipe 25, as pivot point A is capable of moving only along, or parallel to, the longitudinal axis of the housing by virtue of the guide 45 sliding in channels 47, and as pivot point C is fixed to the head of shaft 15, therefore, only pivot point B is free, but it is free to move in but one direction, namely, to project out of the housing 10. The pipe elbow joint 29 and the T-shaped joint 30, constituting pivot point B, are normally in contact with a stop or other abutting member such as the leaf spring 48, secured to the interior of the housing, which is designed to maintain pivot point B slightly out of vertical alignment with relation to points A and C, so that when the pipes 28 and 31 are caused to pivot, as above described, the pivot point B moves outwardly to project the arms into the well hole.

When the pipes 28 and 31 first pivot and move 75

outwardly at point B through the window 24 the upper end 31' of pipe 31 will project further out through the window 24 than the pivot point B, and as pipe 31 is connected to this pivot point at a point intermediate its ends, this results in the upper end of pipe 31 and the cutting heads 39 making an initial contact with the wall of the well hole as shown in Fig. 7. When the cutting heads 39 mounted on the upper end of pipe 31 are thus in contact with the well hole wall the apparatus is then in position to commence the forming of the cavity, or similar enlargement, in the formation. This is accomplished by rotating in either direction and by any suitable means from the surface the pipe or tube 25. By virtue of the lower end of tube 25 being connected to the guide 45 and sliding in channel 47 it causes the entire housing 10 to also rotate. The pipes 28 and 31 will then revolve in a plane about and substantially horizontal to the vertical axis of pipe 25 and housing 10. As shaft 15 is connected to pipe 31 at point C, the shaft will be caused to rotate, but by virtue of the connection between the foot 21 and shaft 15 effected by the dowel pin 22, the foot 21 will remain stationary and merely serve to maintain the housing 10 and the pipes therein contained at the desired height from the bottom of the well hole and opposite the formation thereof in which the cavity is to be formed.

When pipe 25 is initially rotated and pipe 31 is in the position shown in Fig. 8, so that the cutting teeth or heads 39 are contacting the wall of the well hole, the resulting planetary movement of the arms 31 then causes the teeth 39 held against the well hole to cut or wear away the wall thereof to form a cavity therein of symmetrical outline. When the cavity is being formed in a calcareous formation of a well hole, there is at this time introduced into pipe 25, from the surface and preferably under pressure, a chemical such as hydrochloric acid of from about 10 to 25 per cent concentration, or of other suitable strength. The hydrochloric acid is forced down through pipe 25 and into pipes 28 and 31 from whence it will escape through the stub pipes 35 and ports 37 of those cutting heads or teeth which are in contact with the well hole wall with sufficient force to depress the heads 39 and uncover the ports 37. In this manner the acid will assist materially in forming the cavity by attacking and dissolving the same. Any other suitable acid or other chemical may be employed which will dissolve, or partially dissolve, the formation in which the cavity is to be made. For example hydrofluoric acid may be utilized to form a cavity in siliceous formations.

As the pipe 25 is rotated the pipe or arm 31 and the cutting heads 39 guided thereby will be caused to go round and round against the wall of the well hole constantly wearing and cutting it away by the combined action of the cutting teeth and the chemical employed therewith to act on the formation. If substantial pressure is put on the chemical used to assist the cutting teeth in the formation of the cavity, the formation of such a cavity will proceed more rapidly as the chemical issues from the ports 37, or such of them as are opened by the action of the teeth 39 contacting the formation of the well hole, in the form of jets or streams of acid under pressure.

A downward force on pipe 25, applied in any convenient manner from the surface, will cause the cutting heads 39, or at least some of them, to

always be in contact with the formation wherein the cavity is being formed, and will further cause the cutting heads 39 to be more effective in their cutting out of the cavity. Such a downward force may be imparted to the tubing 25 as by weighting the same, or by equivalent means, and the force will in turn be imparted to the arm or pipe 31 to force the teeth into the formation.

Thus it will be seen that only those cutting teeth which are in contact with the formation and engaged in cutting, scraping or otherwise wearing it down to form the cavity therein will be augmented in their cutting action by the escape adjacent thereto of a chemical to assist such forming of the cavity. This is true due to the disc 41 normally being held by the spring 42 so as to cover the ports 37 through which the acid, or other chemicals, may escape. Thus in Fig. 7 which represents an initial stage of forming such a cavity, it will be seen that only the top two or three cutting teeth are engaged in cutting away the well hole wall and only adjacent these cutting heads is there a jet or stream of chemical being released.

As the diameter of the cavity becomes greater and greater the pipe or arm 31 will approach a horizontal, or substantially horizontal position, and more and more of the cutting heads 39 will come into play and contact the formation until all, or substantially all, of the cutting heads are at work on the formation, as illustrated in Fig. 4. In this the outline of the cavity shows it to have been formed to a considerable degree. By this method and apparatus the formation of the cavity progresses gradually and uniformly. The chemical is released in the form of jets only from the cutting heads actually in contact with the formation and being pressed thereagainst by the force applied on them through pipe 25, and in this matter, conservation of chemical is maintained.

When the cavity has been completely formed, the apparatus can be readily removed therefrom by pulling upwardly on pipe 25, which will cause the pipes 28 and 31 to retract within housing 10 and to assume their position as shown in Fig. 1, and the entire apparatus can then be removed from the well hole by raising pipe 25 thus bringing the entire assembly to the surface.

By preliminarily noting on the surface how far pipe 25 has to be depressed downwardly before the hollow arms or pipes 28 and 31 are projected through the window 24 of housing 10 to their maximum possible distance, it can be ascertained later when forming the cavity if the same has been formed to a size as large as is possible with the apparatus at hand.

Obviously, in lieu of the cutting heads or teeth 39 herein illustrated, other types of cutting and/or scraping means may be employed which would still retain the feature of releasing the acid, or other chemical, only when actually in contact with the formation and engaged in forming a cavity therein.

The chemical used in the method may be permitted to escape into the formation or allowed to ascend into the well hole and rise therein to the surface, or be pumped thereto, and if not then exhausted may be reused.

Other modes of applying the principle of my invention may be employed instead of those explained, change being made as regards the method and apparatus herein disclosed, provided the step or steps stated by any of the following

claims or the equivalent of such stated step or steps be employed.

I therefore particularly point out and distinctly claim as my invention:

5. An apparatus for forming a cavity in a well hole, which comprises a housing member adapted to be introduced into the well hole to a point adjacent therein where the cavity is to be formed, a plurality of cutting means carried by said housing member projectible therefrom and rotatable thereby for forming the cavity, and means for supplying an individual stream of liquid adjacent to each of said cutting means to assist it in forming the cavity only when said means is in cutting engagement with the well hole wall.
10. An apparatus for forming a cavity in a well hole, which comprises a string of tubing to be extended into the well hole to a point adjacent therein where said cavity is to be formed, a plurality of individual cutting members suspended by said tubing and moveable thereby to form said cavity, and means for introducing a liquid through said tubing and releasing it in individual streams adjacent said individual members only when each of said members are actively engaged in forming said cavity.
15. An apparatus for forming a cavity in a well hole, which comprises a housing adapted to be extended into the well hole to a point adjacent therein where said cavity is to be formed, an arm having cutting teeth mounted thereon pivotally carried within said housing and outwardly projectible therefrom into the well hole and in contact with the wall thereof to cause the said teeth to contact the formation of said well hole wall, a tubing for causing said arm and teeth to revolve in a substantially horizontal plane about the vertical axis of said well hole, and means for releasing a liquid through said arm to those of said teeth actually engaged in cutting away said formation.
20. An apparatus for forming a cavity in a well hole, which comprises a string of tubing adapted to be extended into the well hole to a point adjacent therein where said cavity is to be formed, an arm having cutting teeth mounted thereon pivotally carried by said tubing and projectable thereby into the well hole and in contact with the wall thereof and rotatable thereby in a substantially horizontal plane about the vertical axis of the well hole, and means for releasing a liquid through said arm to those of said cutting teeth actually engaged in cutting away said formation.
25. An apparatus for forming a cavity in a well hole, which comprises a string of tubing adapted to be extended into the well hole to a point adjacent therein where said cavity is to be formed, an arm having cutting teeth mounted thereon pivotally carried by said tubing and projectable thereby into the well hole and in contact with the wall thereof and rotatable thereby in a substantially horizontal plane about the vertical axis of the well hole, and means for releasing a liquid through said arm to those of said cutting teeth actually engaged in cutting away said formation.
30. An apparatus for forming a cavity in a well hole, which comprises a string of tubing adapted to be extended into the well hole to a point adjacent therein where said cavity is to be formed, an arm having cutting teeth mounted thereon pivotally carried by said tubing and projectable thereby into the well hole and in contact with the wall thereof to cause the said teeth to contact the formation of said well hole wall, a tubing for causing said arm and teeth to revolve in a substantially horizontal plane about the vertical axis of said well hole, and means for releasing a liquid through said arm to those of said teeth actually engaged in cutting away said formation.
35. An apparatus for forming a cavity in a well hole, which comprises a string of tubing adapted to be extended into the well hole to a point adjacent therein where said cavity is to be formed, an arm having cutting teeth mounted thereon pivotally carried by said tubing and projectable thereby into the well hole and in contact with the wall thereof and rotatable thereby in a substantially horizontal plane about the vertical axis of the well hole, and means for releasing a liquid through said arm to those of said cutting teeth actually engaged in cutting away said formation.
40. An apparatus for forming a cavity in a well hole, which comprises a string of tubing adapted to be extended into the well hole to a point adjacent therein where said cavity is to be formed, an arm having cutting teeth mounted thereon pivotally carried by said tubing and projectable thereby into the well hole and in contact with the wall thereof and rotatable thereby in a substantially horizontal plane about the vertical axis of the well hole, and means for releasing a liquid through said arm to those of said cutting teeth actually engaged in cutting away said formation.
45. An apparatus for forming a cavity in a well hole, which comprises a string of tubing adapted to be extended into the well hole to a point adjacent therein where said cavity is to be formed, an arm having cutting teeth mounted thereon pivotally carried by said tubing and projectable thereby into the well hole and in contact with the wall thereof and rotatable thereby in a substantially horizontal plane about the vertical axis of the well hole, and means for releasing a liquid through said arm to those of said cutting teeth actually engaged in cutting away said formation.
50. An apparatus for forming a cavity in a well hole, which comprises a string of tubing adapted to be extended into the well hole to a point adjacent therein where said cavity is to be formed, an arm having cutting teeth mounted thereon pivotally carried by said tubing and projectable thereby into the well hole and in contact with the wall thereof and rotatable thereby in a substantially horizontal plane about the vertical axis of the well hole, and means for releasing a liquid through said arm to those of said cutting teeth actually engaged in cutting away said formation.
55. A device for forming a cavity in a well hole adapted for attachment to the end of a tubing string for lowering into a well, which comprises a tubular housing adapted to be slidably mounted on the lower end of the tubing string, said housing being open along one side thereof, an anchor shaft extending in slidable relation through the lower end of said housing, stop means to limit the travel of said shaft relative to the housing, an anchor attached to the lower end of said shaft by a swivel connection to permit rotary movement of the shaft relative to the anchor, a tubular arm within said housing pivotally connected at the upper end with the lower end of the tubing string and in communication therewith, a second tubular arm pivotally connected at its upper end with the lower end of said first arm and in communication therewith, and at its lower end with the upper end of said shaft, forming a series of three pivot points of which the upper and lower points are fixed and the central point
60. A device for forming a cavity in a well hole adapted for attachment to the end of a tubing string for lowering into a well, which comprises a tubular housing adapted to be slidably mounted on the lower end of the tubing string, said housing being open along one side thereof, an anchor shaft extending in slidable relation through the lower end of said housing, stop means to limit the travel of said shaft relative to the housing, an anchor attached to the lower end of said shaft by a swivel connection to permit rotary movement of the shaft relative to the anchor, a tubular arm within said housing pivotally connected at the upper end with the lower end of the tubing string and in communication therewith, a second tubular arm pivotally connected at its upper end with the lower end of said first arm and in communication therewith, and at its lower end with the upper end of said shaft, forming a series of three pivot points of which the upper and lower points are fixed and the central point
65. A device for forming a cavity in a well hole adapted for attachment to the end of a tubing string for lowering into a well, which comprises a tubular housing adapted to be slidably mounted on the lower end of the tubing string, said housing being open along one side thereof, an anchor shaft extending in slidable relation through the lower end of said housing, stop means to limit the travel of said shaft relative to the housing, an anchor attached to the lower end of said shaft by a swivel connection to permit rotary movement of the shaft relative to the anchor, a tubular arm within said housing pivotally connected at the upper end with the lower end of the tubing string and in communication therewith, a second tubular arm pivotally connected at its upper end with the lower end of said first arm and in communication therewith, and at its lower end with the upper end of said shaft, forming a series of three pivot points of which the upper and lower points are fixed and the central point
70. A device for forming a cavity in a well hole adapted for attachment to the end of a tubing string for lowering into a well, which comprises a tubular housing adapted to be slidably mounted on the lower end of the tubing string, said housing being open along one side thereof, an anchor shaft extending in slidable relation through the lower end of said housing, stop means to limit the travel of said shaft relative to the housing, an anchor attached to the lower end of said shaft by a swivel connection to permit rotary movement of the shaft relative to the anchor, a tubular arm within said housing pivotally connected at the upper end with the lower end of the tubing string and in communication therewith, a second tubular arm pivotally connected at its upper end with the lower end of said first arm and in communication therewith, and at its lower end with the upper end of said shaft, forming a series of three pivot points of which the upper and lower points are fixed and the central point
75. A device for forming a cavity in a well hole adapted for attachment to the end of a tubing string for lowering into a well, which comprises a tubular housing adapted to be slidably mounted on the lower end of the tubing string, said housing being open along one side thereof, an anchor shaft extending in slidable relation through the lower end of said housing, stop means to limit the travel of said shaft relative to the housing, an anchor attached to the lower end of said shaft by a swivel connection to permit rotary movement of the shaft relative to the anchor, a tubular arm within said housing pivotally connected at the upper end with the lower end of the tubing string and in communication therewith, a second tubular arm pivotally connected at its upper end with the lower end of said first arm and in communication therewith, and at its lower end with the upper end of said shaft, forming a series of three pivot points of which the upper and lower points are fixed and the central point

is capable of lateral movement in a vertical plane to project through the open side of said housing, a plurality of outwardly facing cutting members arranged lengthwise of said second arm, means for supplying a cutting fluid through the tubing string and said first arm to the cutting members in said second arm, and means associated with each of said cutting members and ac-

tuated by the external pressure thereon to permit flow of cutting fluid to the working face of the cutting member.

6. A device according to claim 5 in which the cutting members are each mounted on the valve stem of a valve controlling the flow of fluid to the cutting member.

FREDERICK SQUIRES.
